UNITED STATES PATENT OFFICE.

ANTON VON BEUST, OF ORANGE, NEW JERSEY.

POLYCHROMATIC PRINTING-SURFACE AND METHOD OF MAKING SAME.

SPECIFICATION forming part of Letters Patent No. 741,297, dated October 13, 1903.

Application filed February 19, 1903. Serial No. 144,132. (No specimens.)

To all whom it may concern:

Be it known that I, ANTON VON BEUST, a citizen of the United States, residing at Orange, in the county of Essex and State of New Jersey, have invented new and useful Improvements in Polychromatic Printing-Surfaces and Methods of Making the Same, of which the following is a specification.

This invention relates to improved poly-
chromatic printing-surfaces and the method
of making same.

It consists in the improved composition
plate or roll and the method of making same
hereinafter described, and particularly point-
ed out in the claims following the description.

The improved printing-surface hereinafter
described is primarily designed for marble-
izing or illuminating the edges and faces of
books and the like, though it may be employed
for various other purposes, as will hereinafter
more fully appear.

The compound printing plate or roll may
be made from more than one formula of in-
gredients, and the proportions employed may
vary under different conditions; but the prin-
cipal material employed is a color or pig-
ment, and for the purpose anilin colors are
preferred. Such coloring-matter is incorpo-
rated in a pliant material, preferably of a
glutinous nature, and I prefer to add thereto
soap, which allows impressions to be readily
taken from the finished plates or rolls. There
should also be added a sufficient part of gly-
cerin to prevent the mass from drying out too
quickly and carbolic acid to prevent decom-
position of the plate or roll.

The proportions of the substances used will
vary with different colors and also with dif-
ferent temperatures and seasons of the year.

The preferred plate or roll is constructed
as follows: I dissolve thoroughly three parts
of anilin color in three parts of glycerin, the
two being ground together in a mortar. I
add the anilin color and glycerin slowly to a
hot composition consisting of three parts of
glue and one part of soap, previously boiled
together over a hot-water bath, and keep stir-
ring the mass constantly while over the fire,
and then add a few drops of carbolic acid.
The mass is then poured into a greased pan
and allowed to become cool until it becomes
of the consistency, say, of comparatively soft

rubber. The above operation is repeated as
often as it is necessary to provide the num-
ber of different colors desired, each separate
mass having incorporated therein its own dis-
tinctive color. The coloring-matter added to
each batch or mass will be varied with a view
to obtaining light or dark shades, as may be
desired. When all the differently-colored
masses are cold and stiff, they are taken from
the pans and chopped or ground up or other-
wise suitably disintegrated into particles or
pieces of more or less fineness to obtain the
effect desired. If desired, more of one col-
ored mass than another may be taken, as
may be necessary to effect the desired result.
When all the differently-colored masses are
disintegrated, they are mixed, so as to cause
them to spread through one another evenly,
and are placed in a greased pan or into a cy-
lindrical mold and are gently heated over a
steam or hot-water bath to cause the differ-
ently-colored masses to assume a plastic state
and run one into the other to form a homo-
geneous mass. When the colored masses are
melted, the tray or cylindrical mold should be
agitated in any suitable manner in order to
cause the masses to flow together and assume
a streaked or marbled appearance. The com-
pound is then allowed to cool, after which it is
removed from the pan or mold, and the plate
or roll thus formed is finished and ready for
transferring the colored design to the object
to be ornamented. In ornamenting the edges
of a book, for example, a sponge or brush
dipped in a thin starchy paste is first passed
over the edges of the book, and the composi-
tion-roll formed, as hereinbefore described,
is rolled over the edges of the book, or the
edges of the book are applied to the surface
of the plate. In this manner any material to
be ornamented is treated by the roll or plate.
While the composition plate or roll before
described is primarily intended for marble-
izing or decorating the edges and covers of
books, it may be used for many other pur-
poses—for example, it may be employed to
illuminate magazine-covers, newspaper-cov-
ers, stationery, and for forming borders
around illustrations. It may also be employed
for illuminating fancy and other papers, such
as packing-papers, for example. In the lat-
ter case a contact-roller constructed in the

manner described can be placed in a paper-machine and the paper passed over the same while still damp and before it is quite finished. In such case the compounded roller is 5 of great value to paper-manufacturers, inasmuch as no extra machinery is required and the paper need not be handled a second time after its manufacture. It is also of value to decorators, as it can be used directly on plastered walls of houses. The walls are first sized, and the compound roller is passed over the surfaces of the walls and impresses its 10 design thereon. When dry, the surfaces may be varnished or otherwise finished to 15 protect the imprint. It may also be used for printing wall-paper, or decorating oil-cloth, woodwork, celluloid, and the like. In fact, it may be employed for imparting a colored decorative design to any article or substance.

20 Having thus described my invention, what I claim as new, and desire to secure by Letters Patent, is—

1. The process herein described of making polychromatic printing-surfaces, consisting 25 in making several separate gelatinous compounds, incorporating in each separate mass a distinctive coloring substance, permitting the latter to become stiff, separately disintegrating each of said masses, mixing such dis-

integrated masses in a mold, and finally subjecting such mold to heat to cause said separately-colored masses to melt and run together, for the purpose specified. 30

2. The process herein described of making polychromatic printing-surfaces consisting 35 in making several separate gelatinous compounds, incorporating in each separate mass a distinctive coloring substance, permitting the latter to become stiff, separately disintegrating each of said masses, mixing said disintegrated masses in molds, and finally subjecting such molds to heat to cause said separately-colored masses to melt and run together, and agitating such molds while the mass is in a melted condition, for the purpose 40 specified. 45

3. As a new article of manufacture, a printing composition consisting of glycerin, glue, soap, carbolic acid and a coloring substance compounded substantially in the manner and 50 in the proportions specified.

In testimony whereof I have hereunto set my hand in presence of two subscribing witnesses.

ANTON VON BEUST.

Witnesses:

J. WARREN SMITH,
CHAS. HASLER.
